UNITED STATES PATENT OFFICE.

SAMUEL G. THOMSON, OF READING, PENNSYLVANIA.

STEAM-BOILER FURNACE.

1,147,567.

Specification of Letters Patent.

Patented July 20, 1915.

Application filed February 3, 1913. Serial No. 745,882.

To all whom it may concern:

Be it known that I, SAMUEL G. THOMSON, a citizen of the United States, and resident of Reading, Berks county, Pennsylvania, have invented a new and useful Improvement in Steam-Boiler Furnaces, of which the following is a full, clear, and exact description, reference being had to the accompanying drawings.

10 The several figures of the drawings are more or less conventional or diagrammatic. Figures 1 and 2 are plan views illustrating the simplest forms of my invention as applied to a locomotive; Fig. 3 is a side view of the arrangement shown in Fig. 2; Fig. 4 is a view similar to Fig. 3 but showing a modification; Fig. 5 is a plan view of Fig. 4; Fig. 6 is an end view; Figs. 7 and 8 are detail sectional views; Figs. 9, 10 and 11 are detail sectional views showing various arrangements of the exhaust pipe connection.

My invention has relation to steam boiler furnaces, and it consists in the provision of 25 improved means for increasing the combustion by drawing steam through the fire. For this purpose I preferably make use of the forced draft caused by the exhaust of the engine. The suction produced on the 30 fire by the exhaust in the stack draws steam through the hot bed of coals so rapidly that the steam is decomposed into hydrogen and oxygen. The result is that both the hydrogen and oxygen burn to create a very intense heat, the oxygen burning rapidly on 35 account of being liberated in an atmosphere of free hydrogen. Large quantities of wet steam can thus be used to add to the combustion gases of the boiler, the steam being 40 preferably exhaust steam, which is entirely a waste product, and the wetter it is the better it serves the purpose.

My invention provides for the utilization 45 of the exhaust steam from the engine supplied by the boiler, and is particularly adapted for use on locomotives, although it may be applied with advantage to stationary boilers. It also preferably provides for the utilization of steam from the exhaust of 50 the air-pump engine, and also, when desired, for use in connection with the exhaust steam of a proper amount of live steam taken directly from the boiler. Where steam is used from more than one source, valve

means are provided whereby the supply 55 from each source can be readily controlled.

My invention also provides means of novel character for blowing the collected ashes from the flaring sides of the ash pan into the central portion of the ash pan.

Another object of my invention is the utilization of the steam to prevent clinkering in the fire box.

Referring first to the diagram of Fig. 1, in which I have shown the simplest form of 65 my invention, the numeral 2 designates the boiler, 3 the fire box, and 5 the cylinders of an ordinary locomotive. 6 designates a pipe, which leads from the exhaust of one or both of the cylinders 5 into the ash pan 70 of the fire box below the grate. When the locomotive is working, a certain amount of the exhaust steam from the cylinders is fed into the fire automatically by the pipe 6, the amount of this exhaust steam depending 75 upon the size of this pipe and the arrangement of the openings in the exhaust cavity. When the locomotive is not working, no steam is discharged under the fire. That is to say, steam is only furnished to the fire 80 when there is a strong exhaust to pull it through the coals. The pipe 6 has a branch 7 communicating with the exhaust of the engine of the air pump 8. In this form, the air pump engine discharges part of its exhaust steam under the fire when the locomotive is not working its steam cylinders, the remaining part of the air pump exhaust 85 coming out of the stack in the usual manner, the proportion of exhaust steam coming 90 each way depending on the size and arrangement of the pipes. When the locomotive is working steam in its steam cylinders, the pressure of the exhaust from the steam cylinders automatically drives all of the air 95 pump exhaust steam into the ash pan, thus supplying very large quantities of wet steam under the fire. In this way, as much wet steam can be supplied as can be advantageously utilized to intensify the combustion 100 without dampening the fire.

Fig. 2 shows an arrangement similar to Fig. 1, but in this case the pipe 6 has one branch 9 discharging into the front portion 105 of the ash pan and another branch 10 discharging into the back portion of the ash pan. A valve 11 is also added between the juncture of the air pump exhaust and the

ash pan. This valve can be operated by suitable actuating connections 12, leading into the engine cab. By the provision of this valve, the supply of steam under the 5 fire can be cut off or adjusted according to the work the locomotive is doing, the condition of the fire, the quality of coal which is being used, etc.

Fig. 3 shows in diagram an elevation of a 10 locomotive having a similar arrangement to that shown in Fig. 2, except that a valve 13 is provided which can be closed to cause all of the exhaust steam in the steam cylinders to exhaust into the stack at 13^b. With 15 this valve closed and the valve 13^a opened, all of the air pump exhaust steam will go into the ash pan.

Figs. 4 and 5 show substantially the same arrangement as that shown in Fig. 3, except that they are more complete, Fig. 5 20 showing two of the pipes 6, one connecting with the exhaust of each cylinder 5, and each pipe having a plurality of discharges along the sides of the ash pan in addition to the 25 branches 9 and 10 before described and leading into the front and back portions of the ash pan respectively. In these figures I have also shown a connection 14 connecting 30 one of the pipes 6 with one of the steam domes 15 of the locomotive boiler. This pipe connection 14 has a valve 15^a, and may be used for the purpose of introducing live 35 steam from the locomotive boiler to blow down the ashes from the sides of the ash pan, or for introducing live steam to facilitate 40 the combustion and disintegrate the clinker on the grates, when the exhaust steam is not of sufficient capacity.

The exhausts along the sides of the ash 45 pan are in the form of jet nozzles 16, their arrangement being more clearly shown in Figs. 6, 7 and 8. These nozzles may be directed at any desired angle, these three figures showing different angular arrangements. In Fig. 8 the pipe is shown as being 50 within the upper portion of the ash pan, while in Fig. 7 it is shown as extending along the outer side thereof, the nozzles 16 projecting through an opening which is 55 formed between the upper edge of the outwardly flaring portions 16^a of the fire box, over the wheels, and the bottom of the mud ring 16^b.

In Figs. 9, 10 and 11 I have illustrated 60 different forms of the connection between the intake end of one of the pipes 6 and the exhaust cavity 17 of the steam engine. The intake end of the pipe may be made flush with the inside of the exhaust cavity, as 65 shown in Fig. 11, in which case, on account of the pressure of the steam as it comes out of the cylinder, some of the exhaust will be forced back through the pipe 6 into the ash pan. If the end of the pipe 6 is curved

70 downwardly, as shown at 6^a in Fig. 10, or is 75 beveled as shown at 6^b in Fig. 9, it will 80 entrap more steam on account of the velocity of the steam being added to the pressure. Various other arrangements of the intake 85 end of the pipes 6 can be made without departing from my invention. Thus, the pipe shown in Fig. 11 may move to vary the extent of its projection in to the exhaust cavity 17 and thus vary the amount of steam 90 which is entrapped.

The principle of my invention differs fundamentally from the practice of admitting live steam direct from the boiler itself into the ash pit of the stationary boiler through the agency of a fan, such as is frequently 95 used for the purpose of preventing clinker from forming over the grates. In such an arrangement, the success or failure of the system depends on the furnishing of steam by the fans in exactly the right proportion for the air that is drawn in with it in order that the oxygen of the air may be sufficient to burn the clinker. If the right amount of air is not supplied, the practice is a failure, and the steam causes a dampening of the fire 100 and a consequent loss instead of gain in heating capacity. Under the best conditions in which these fans are used on the stationary boilers, the live steam employed 105 furnished very little water; and what is furnished usually passes through the fire and out through the tubes without the heat becoming high enough to decompose the water into its component parts. With my arrangement, the strong suction over the fire, 110 caused by the engine exhaust, draws the wet steam into and through a very hot fire before it has had a chance to dampen the coal. It thus comes into contact with the heat, which frees the oxygen and hydrogen and 115 causes them both to burn. The disintegration of the wet steam begins at about 1,000 degrees Fahrenheit, and is well completed at about 2,500 degrees Fahrenheit. This 120 disintegration is only possible where the fire is forced, as by my method of exhaust suction. The high temperatures developed—which probably reach the neighborhood of 3,000 degrees Fahrenheit,—are indicated by the presence of white molten slag through 125 the body of the coal, this slag being burned to a crisp, so that it falls to pieces and does not clog the fire. The disintegration of the wet steam and the burning up of the clinker is one of the greatest advantages of my improvement. Experience has shown that it effects even a greater economy in the cost of labor it saves in cleaning fires, than the economy caused by the addition of the oxygen and hydrogen from the steam and the combustion gases, and the added amount of carbon which their burning together causes to be consumed.

My improvement, as applied to locomotives, effectively disintegrates all clinker, so that even when burning very bad coal, the fires can be kept clean by shaking the ashes through the grates. The ashes fall through the grates in very small particles instead of running together and clinkering in large lumps. This enables locomotives to be kept in service for several days at a time without having their fires cleaned, it only being necessary to go to the ash pit to empty the ash pan. This is a great saving in labor over the usual practice, where an engine must have its fire cleaned every few hours in order to obtain proper draft and prevent the fire box filling up with ashes.

By utilizing the exhaust from the air-pump engine, as well as that from the steam cylinders, a portion of the air-pump exhaust may be diverted under the grates while the locomotive is not working. As soon as the locomotive starts to use steam in the cylinders, and thereby brightens the fire, all of the air-pump exhaust is driven backward under the grates, together with the exhaust steam entrapped from the cylinders. In this manner the air-pump exhaust steam is automatically used under the fire when needed, and is diverted into the stack when not needed.

The system can be arranged to exhaust the steam into the ash pan at a considerable distance below the grates, or through small openings arranged along the sides of the pan immediately under the grates, according to the shape of the ash pan. On ash pans with wide fire boxes it is of advantage to have both types of openings into the pan, the jets along the sides of the fire box being used to distribute the steam close to the side sheets of the fire box and also to keep the flaring sides of the fire box clear of ashes.

It will be obvious that my invention is susceptible of various other modifications in its details of construction and arrangement besides those which I have shown and described.

I claim:—

1. A locomotive having a steam exhaust pipe leading from its steam cylinders into its ash pan, and having an air pump exhaust pipe emptying into said steam pipe.

2. A locomotive having a steam exhaust pipe leading from its steam cylinders into the ash pan, and another pipe leading from its air-pump exhaust and connecting with the first-named pipe, said connections providing means whereby the air pump exhaust steam is driven into the ash pan when there is exhaust steam escaping from the steam cylinders.

3. A locomotive having a steam exhaust pipe leading from its steam cylinders into its ash pan, and another pipe leading from the exhaust of its air-pump and connecting

with the first named pipe, said exhaust pipe having a valve between the juncture of the pipes and the ash pan.

4. A locomotive having a steam exhaust pipe leading from its steam cylinders into its ash pan, and another pipe leading from the exhaust of its air-pump and connecting with said exhaust pipe, the exhaust pipe having a valve between the juncture of said pipes and the steam cylinders.

5. A locomotive having a pipe leading from the exhaust port of its steam cylinders and the exhaust opening of its air-pump into the space in the ash pan below the fire grates of the locomotive, a portion of said pipe carrying the exhaust steam from both of these sources.

6. A locomotive having a pipe leading from the exhaust port of its steam cylinders and the exhaust opening of its air-pump into the space in the ash pan below the fire grates, said pipe having a valve to restrict or shut off said exhaust.

7. A locomotive having a pipe connected with the exhaust port of its steam cylinder, and also with the exhaust from its air-pump, said pipe extending along the ash pan immediately below the mud ring of the fire box and having discharge openings to admit steam below the grates, said pipe having valves arranged to control the steam from either source, the exhaust steam from the steam cylinder acting to force exhaust steam from the air pump through said pipe.

8. A locomotive having a pipe connected with the exhaust port of its steam cylinders, and also with the exhaust from its air-pump, and provided with valves to control the amount of steam admitted from either of said sources, said pipe also having a branch connected with the steam space of the locomotive boiler, the pipe extending along the side of the ash pan and having a plurality of discharge apertures to admit steam under the grate, the exhaust steam from the steam cylinder acting to force exhaust steam from the air pump through said pipe.

9. A locomotive having a steam pipe connected with the locomotive boiler and extending along the side of the ash pan immediately under the mud ring of the fire box, and provided with a plurality of openings or nozzles at intervals arranged to blow jets of live steam into the ash pan, and means for connecting said nozzles with the exhaust from the air pump and steam cylinders.

10. A locomotive having a system of piping connected to the exhaust of its steam cylinders and also to the exhaust of its air-pump, and also to the steam space of its boiler, said system of piping having an opening into the ash pan below the grates, and having valves so arranged in its

branches that steam can be admitted under the grates from any one or all of the several sources of steam, said pipes being so arranged that the exhaust from the steam cylinders drives the air pump exhaust steam into the ash pan.

11. A locomotive having a pipe connected to the exhaust of its air pump, said pipe having a connection to the exhaust of the locomotive steam cylinders and being ar-

ranged to deliver the exhaust steam from the air-pump into the ash pan by means of the pressure of the exhaust steam from said pipe to the locomotive steam cylinders.

In testimony whereof, I have hereunto 15 set my hand.

SAMUEL G. THOMSON.
